C. L. DRAKE

MECHANICAL FIGURE TOY

Filed Jan. 27, 1925

UNITED STATES PATENT OFFICE.

CHARLES L. DRAKE, OF WEST LOS ANGELES, CALIFORNIA.

MECHANICAL FIGURE TOY.

Application filed January 27, 1925. Serial No. 5,145.

To all whom it may concern:

Be it known that CHARLES L. DRAKE, a citizen of the United States, residing at West Los Angeles, in the county of Los Angeles and State of California, has invented a new and useful Improvements in Mechanical Figure Toys, of which the following is a specification.

This invention relates to toys and has for its major object the provision of simple means to operate a pair of figures to simulate a boxing contest or the like.

A further and equally important object of the invention is to provide novel means whereby the figures are caused to assume a variety of positions to imitate various boxing maneuvers such as getting away, ducking, slipping, clinching, upper-cutting, rabbit-punching, pivot-punching, stalling, blocking, hitting off the block, etc., all without going through any fixed cycle of operation.

A further object of the invention is to provide a toy of the character specified which is of highly simplified construction, durable in use, and cheap to manufacture.

Other objects and advantages will be apparent during the course of the following description:

In the accompanying drawing forming a part of this application, and in which like numerals are employed to designate like parts throughout the same,

Figure 1 is a vertical sectional view through the improved toy.

Figure 2 is a horizontal sectional view through the same.

In the drawing, wherein for the purpose of illustration is shown a preferred embodiment of the invention, the numeral 5 designates a casing, the top of which is designated by the numeral 6, and which forms more or less of a platform upon which the figures which participate in the simulated boxing contest are mounted.

In carrying out the invention a pair of posts 7 are arranged vertically within the casing 5 and are rotatably extended through the top 6 for supporting an operating disk or head 8, the said head or disk 8 being securely connected to the post 7 by a nut 9 or other suitable fastening device.

Attention is directed to the fact that the posts 7 may be rocked by cranks 11 having

connection with thongs or links 12 by pivot elements 13. The outer portions of the thongs or links 12 have connection with a longitudinally movable plunger 14, slideable through the casing and having a handle arranged exteriorly of the casing to form a means whereby the plunger may be manually or otherwise reciprocated for imparting the desired rocking movement to the posts 7. When the plunger or main operating member 14 is advanced it may be released so that coil springs 16 connected to the cranks 11 may contract and return the posts to their original or normal positions. This may be repeated a number of times to impart the rocking movement to the posts 7 and the heads or disks 8 associated therewith.

Figure 1 plainly illustrates that figure supporting disks or members 20 are loosely mounted upon the outer ends of the posts 7 by fastening devices 22, and the heads of these fastening devices are spaced a sufficient distance above the nuts 9 to allow the disks 20 to partake of a rather free and loose-jointed tilting movement on the upper portions of the posts. This permits the disks 20 to be tilted above and below the horizontal in the operation of the toy.

The upper sides of the disks 8 are provided with struck-up or other lugs 24 adapted to engage lugs or similar striking devices 26 extending from the lower sides of the figure supporting disks 20. When the lugs 24 strike the lugs 26, a rotating and possibly rocking movement is imparted to the disks 20 and the figures mounted thereon. As the disks 8 operate in clockwise and anti-clockwise directions, a similar movement will be imparted to the upper disks 20. However, as there is no positive or constant connection between the upper and lower disks, or the lugs of the same, the upper disks will not closely follow the movements of the lower disks. This avoids a regular cycle of operation and also allows one upper disk to partake of an entirely separate movement from the other upper disk.

Figure 1 plainly illustrates that standards 30 are rigidly secured to the edge portions of the disks 20 and are disposed at acute angles with respect to the planes of the disks so that the figures 32 carried by the standards will more effectively weigh down

one side of each upper disk. In other words, each upper disk is provided at the edge portion thereof with a single weighted figure which causes the disk to normally occupy an inclined position as illustrated in Figure 1.

Rigid arms 36 have a more or less swivelled and ball and socket connection 38 with the shoulders of the figure so as to permit the arms to partake of free swinging movement when the disks are operated.

The links 40 of the figures have a somewhat swivelled and ball and socket connection 42 with the bodies of the figures, and these links 40 may consist of upper and lower sections loosely connected as indicated at 44. Of course, suitable means may be provided to limit the movement of the extremities of the figures with respect to the bodies.

In operation, it is merely necessary to reciprocate the plunger 14 to impart the previously described rocking movement to the posts 7 and the disks 8 associated therewith. When the disks 8 are thus rocked in clockwise and anti-clockwise directions, the lugs 24 carried by the same will engage the lugs 26 to turn the upper disks 20 and to tilt the same about the horizontal. Of course, the upper disks 26 normally occupy slightly tilted positions, but these positions may be momentarily varied when a driving connection is established by reason of the contact of the lugs 24 with the lugs 26.

It will be seen that the relation of the upper disks 26 to the lower and driving disks 8 is constantly being varied and this causes the figures 32, which appear in the form of boxers, to assume a wide variety of positions with relation to each other.

The arrangement described provides a means whereby the boxers can assume positions in imitation of leading, swinging, getting away, ducking, slipping, clinching, upper-cut'in', pivot-punching, stalling, blocking, hitting off the block, etc. Of course, this cycle of movement is not carried out in the order mentioned, as the boxers will seldom resume any previously taken positions with relation to each other.

The head 80 has a more or less loose jointed connection 81 with the body of the figure so it can move in response to the movements of the body. Attention is also directed to the fact that the pin 84 which connects the body of the figure to the post 30 allows the body to swing a limited extent on the post.

It is to be understood that the form of invention herewith shown and described is to be taken merely as a preferred example of the same and that such minor changes in arrangement and construction of parts may be made as will remain within the spirit of the invention and the scope of its claims.

Having thus described my invention what I claim as new and desire to secure by Letters Patent is:—

1. A toy comprising supports, base members rotatably and loosely mounted on the supports for turning and tilting movement, and figures mounted on the base members adjacent the edges of the same.

2. A toy comprising supports, base members rotatably and loosely mounted on the supports for turning and tilting movement, and figures mounted on the base members adjacent the edges of the same, and having movable arms.

3. A toy comprising a pair of base members arranged adjacent each other, means to rotatably support the base members for turning and tilting movement, figures having standards mounted on said base members at points spaced from the centers of the same.

4. A toy comprising a pair of base members arranged adjacent each other, means to rotatably support the base members for turning and tilting movement, and figures having standards mounted on said base members at points spaced from the centers of the same, and driving members arranged beneath said base members and having means to turn the base members back and forth and to tilt the same.

5. A toy comprising a pair of base members arranged adjacent each other, posts having means to support said base members for free rocking and tilting movements, standards connected to the base members adjacent the outer edges thereof and being arranged at acute angles to the planes of the same, and figures having connection with the standards and being provided with loose-jointed extremities.

6. A toy comprising a pair of base members arranged adjacent each other, posts having means to support said base members for free rocking and tilting movements, standards connected to the base members adjacent the outer edges thereof and being arranged at acute angles to the planes of the same, and figures having connection with the standards and being provided with loose-jointed extremities, and driving members having means to engage said base members to rock and tilt the same.

7. A toy comprising a pair of base members arranged adjacent each other, rotatable posts having means supporting said base members for free turning and tilting movements, standards connected to the base members adjacent the outer edges thereof and being arranged at acute angles to the planes of the same, and figures having connection with the standards and being provided with loose-jointed extremities, and driving members having means to engage said base members to turn and tilt the same, and means to turn said posts.

8. A toy comprising a casing, rotatable posts extending through the casing, disks mounted on said posts and having lugs, upper disks mounted on the upper portions 5 of said posts and having lugs engaged by said first named lugs, means loosely connecting the upper disks to said posts whereby the upper disks may partake of free rocking and tilting movement irrespective 10 of the first named disks, and means to turn said posts.

9. A toy comprising a casing, rotatable posts extending through the casing, disks mounted on the upper portions of said posts 15 and having lugs, upper disks mounted on the upper portions of said posts and having lugs engaged by said first named lugs, means loosely connecting the upper disks to said posts whereby the upper disks may partake 20 of free rocking and tilting movement irrespective of the first named disks, means to turn said posts, and boxing figures having standards mounted on said upper disks.

10. A toy comprising a casing, rotatable posts extending through the casing, disks mounted on the upper portions of said posts and having lugs, upper disks mounted on the upper portions of said posts and having lugs engaged by said first named lugs, means 25 loosely connecting the upper disks to said posts whereby the upper disks may partake of free rocking and tilting movement irrespective of the first named disks, and means to turn said posts, and boxing figures having standards mounted on said upper disks and adapted to assume a variety of positions with respect to each other, said standards being disposed at acute angles with respect to the planes of said upper disks.

40 11. A toy of the character specified comprising a casing, posts carried by the casing, driving disks mounted on said posts, driven disks mounted on the upper portions of the posts, means extending axially through the driven disks and loosely connecting the driven disks to the posts whereby the driven disks may partake of free rocking and tilting movements with respect to the driving disks, the opposed sides of said driving and driven 45 disks being provided with lugs adapted for

engagement with each other, a standard on each driven disk, each standard being provided with a figure.

12. A toy of the character specified comprising a casing, posts rotatably carried by 55 the casing, driving disks mounted on said posts, driven disks mounted on the posts, means loosely connecting the driven disks to the posts whereby the driven disks may partake of free rocking and tilting movements with respect to the driving disks, the opposed sides of said driving and driven disks being provided with lugs adapted for engagement with each other, a standard on 60 each driven disk, each standard being provided with a figure, cranks having connection with said posts, and arranged within said casing, thongs connected to said cranks, and a plunger connected to said thongs and 65 slidable through opposite sides of said casing and guided thereby.

13. A toy of the character specified comprising a casing, posts rotatably carried by the casing, driving disks mounted on said posts, 75 driven disks mounted on the posts, means extending axially through the driven disks and loosely connecting the driven disks to the posts whereby the driven disks may partake of free rocking and tilting movements with respect to the driving disks, 80 said driving and driven disks being provided with lugs adapted for engagement with each other, a standard on each driven disk, each standard being provided with a figure, crank having connection with said 85 posts and spring means connected to said cranks to return said posts to their normal positions upon being released.

14. A toy of the character specified comprising a casing, posts rotatably extended 90 through the casing and having cranks, springs normally holding the cranks in position, thongs connected to the cranks, and a plunger slidable through the casing and guided thereby and having connection with 95 said thongs, and figures operated by said posts.

In testimony whereof I affix my signature.

CHARLES L. DRAKE.
